UNITED STATES PATENT OFFICE.

WILL FITZ AND PETER FITZ, OF BREMOND, TEXAS.

ROCKER ATTACHMENT.

1,252,418.

Specification of Letters Patent.

Patented Jan. 8, 1918.

Application filed February 20, 1917. Serial No. 149,832.

To all whom it may concern:

Be it known that we, WILL FITZ and PETER FITZ, subjects of the Emperor of Germany, residing at Bremond, in the county of Robert-
son and State of Texas, have invented cer-
tain new and useful Improvements in Rocker
Attachments, of which the following is a
specification.

This invention relates to furniture and
10 has special reference to a rocking chair pro-
vided with a resilient cushion for the
rockers.

One important object of the invention is
to improve and simplify the general con-
15 struction of devices of this character.

A second important object of the invention
is to provide a device of this character
wherein a spring metal channel will be used
in connection with the rocker of a chair,
20 the arrangement of the parts being such that
a high degree of cushioning is effected.

A third important object of the invention
is to provide a device of this descrip-
25 tion which may be applied to any rocking
chair of the ordinary form in a very simple
manner.

With the above and other objects in view,
as will be hereinafter apparent the invention
30 consists in general of certain novel de-
tails of construction and combinations of
parts hereinafter fully described, illustrated
in the accompanying drawing, and specifi-
cally claimed.

In the accompanying drawing, like char-
35 acters of reference indicate like parts in the
several views, and:—

Figure 1 is a perspective view of a por-
tion of the rocking chair showing the de-
vice applied thereto.

40 Fig. 2 is a transverse section through a
rocker with the device applied thereto.

Fig. 3 is a longitudinal section on the line
3—3 of Fig. 2.

In carrying out the objects of this in-
45 vention there is provided a U-shaped strip
10 of spring metal which has flaring sides
11. This strip of metal is of sufficient length
to extend from one end of a rocker R to
the other and is entirely surrounded by an
50 elastic covering element 12, preferably india
rubber or the like, as clearly shown in Fig.
2. Extending upward from the strip 11
are a series of integral stems 13 threaded at
their upper ends as indicated at 14. These

5 stems 13 pass slidably through suitable open-
ings 15 in the rocker R and on the upper
end of which stem is provided a washer 16
and nut 17 the latter being preferably a
butterfly nut. Now it will be observed from
60 an inspection of Fig. 2 that the arrangement
is such that the rocker is wedged into the
channel like cushioning member and it will
be obvious that different widths of rockers
may be wedged in this member in this way
the rockers being held in position by the
65 nuts 17. Now, when weight is applied to
the chair the rocker will slide downward to
a certain small extent the downward move-
ment being resisted by the resiliency of the
spring strip. Moreover, it will be noted
70 that this downward movement is permitted
by the sliding of the stems through the
rocker. When the weight is removed then
the contraction of the side edges of the cushion-
ioning member will force the rocker up-
75 ward, the angle of the sides being always
sufficient for this purpose.

There has thus been provided a simple
and efficient device of the kind described
and for the purpose specified.

It is obvious that many minor changes
may be made in the form and construction
of the invention without departing from the
material principles thereof. It is not there-
fore desired to confine the invention to the
85 exact form herein shown and described but
it is wished to include all such as properly
come within the scope claimed.

Having thus described the invention, what
is claimed as new, is:—

90 The combination with a resilient cushion-
ing member comprising a U-shaped strip
of spring metal having flaring sides, an
elastic cover entirely surrounding said
strip, a rocker wedged between the sides of
95 said member in spaced relation to the bight
portion thereof, stems extending upward
from the spring metal strip and passing
through the rocker and nuts on the upper
ends of said stems above the rocker.

100 In testimony whereof we affix our signa-
tures.

WILL FITZ.
PETER FITZ.

In the presence of—

MARY K. FLAHERTY,
MARIE H. ZBIERAJEWSKA.
